UNITED STATES PATENT OFFICE

GEORGE HENRY WALKER, OF WORCESTER, ENGLAND, ASSIGNOR TO HEENAN & FROUDE
LIMITED, OF WORCESTER, ENGLAND

HYDRAULIC CLUTCH

Application filed June 16, 1930, Serial No. 461,610, and in Great Britain September 7, 1929.

This invention relates to improvements in hydraulic clutches of the type described in the specification of my prior application Serial No. 331,358 filed January 9th, 1929, 5 in which power is transmitted from the driving to the driven element by hydraulic reaction without the aid of solid friction.

In clutches of this type it has hitherto been the practice to construct the clutch so that it 10 remains under running conditions, either full or empty of the power transmitting liquid and no means have hitherto been provided so that it will run continuously in a condition intermediate between full and 15 empty.

One object of the present invention is to provide means for controlling the rate at which liquid is allowed to leave the power transmitting portion of the clutch so that 20 the amount of slip between the driving and driven elements can be regulated and a further object is to attain a better control of the rate of admission than has hitherto been attainable.

25 A further object of the invention consists in providing the clutch with means for causing and controlling cavitation of the vortices which are created in the cups of the clutch elements by the circulation of liquid 30 which takes place under running conditions.

The invention comprises two elements, a rotor and an outer casing both of which are adapted to rotate and which are formed with cups or pockets in which liquid circulates, 35 passages being formed in the vanes separating the cups for the admission of cooled liquid and a further passage or passages in one or more of the vanes by which the centres of the vortices can be placed in communication with 40 the external atmosphere to vary the power transmitted by the clutch.

The invention will be described with reference to the accompanying drawings:—

Fig. 1 is a vertical section through the 45 clutch.

Fig. 2 is a part vertical section through the clutch showing means for preventing fluctuation in speed in one of the shafts.

Figs. 3, 4 and 5 are detail sections showing three forms of release valve.

Fig. 6 is a detail section of a modified de-clutching valve.

Fig. 7 is a part front elevation of a rotor member.

Fig. 8 is a section on line 8—8 Fig. 7.

Fig. 9 is a section on line 9—9 Fig. 8.

In the arrangement shown in Fig. 1 the clutch B is mounted to transmit power from an electric motor shaft A or other source of power to a driven shaft C driving a fan 60 or other machine (not shown).

The clutch B is formed with two elements B¹, B² of the type referred to in my prior application Serial No. 331,358 filed January 9th, 1929, with however a series of air vents 65 b connecting the external atmosphere with the centre of the vortices in the working compartment of the clutch where under running conditions the pressure is low.

When the cups of these elements are packed full of liquid, the clutch works at maximum efficiency, transmitting power with a minimum amount of slip between the driving and driven shafts.

If however the clutch is allowed to empty 75 itself partially the liquid which remains in circulation tends to cavitate and cling to the periphery of the cups while the cavity at the centre of the vortex becomes filled with atmospheric air admitted through the vent pipes b. When running under this condition, the degree of slip between the driving and driven shafts is greater than if the cups remained full of liquid and by suitably controlling the admission and egress of liquid 80 to and from the clutch, the cavitation and the amount of slip can be varied within wide limits.

Liquid is admitted to the cups through an inlet pipe E passing through inlet passages 90 b¹ in one or more of the vanes separating the cups, the flow of liquid being controlled by hand operated or other valve e. The elements are enclosed by a rotating cover plate B³ 95 which is bolted to one of the elements.

In order to prevent overheating of the liquid, a circulation is provided by fitting the cover plate B³ with discharge plugs or valves B⁴ fixed in any suitable position. Details of the discharge valves b are shown in 100

Figs. 3 to 5 and will be described hereafter. Hitherto it has been the practice to arrange such outlets at a point near the periphery where centrifugal force creates a pressure which was always assumed to be necessary to promote the escape of liquid.

It has been found however, that when transmitting power, the relative movement of the clutch elements generates a pressure of liquid which is additional to that created by centrifugal force, and tends to cause the liquid to fill all parts of the revolving clutch casing except those near the vortices where cavitation occurs. By taking advantage of this pressure and providing the outlets near the axis the effects of centrifugal force on the rate of discharge of the liquid are overcome.

The liquid after passing into the cups through the passages b^1 overflows during rotation of the members into the chamber formed between the walls of the element B^2 and the cover plate B^3 from which it is discharged when the pressure in this chamber has reached a predetermined value through the valves B^4 into the stationary casing B^5 from which it escapes through an outlet b^2 .

In operation the rate of feed is rendered uniform by supplying liquid to the inlets E and b^1 at uniform velocity, by maintaining a uniform pressure at the intake and a constant orifice or hand or otherwise controlled valve e^1 in the inlet pipe E . The liquid is discharged from the clutch casing through the outlet valves B^4 at a rate which depends upon the pressure of liquid created inside the cover plate B^3 . This cover plate B^3 is in free communication with the working compartments or cups; and as the pressure of liquid is primarily a function of the torque, if the torque rises in excess of the predetermined maximum, the pressure at the outlet valve B^4 also increases and the liquid emerges more rapidly. Meantime, there is no corresponding increase in the rate of supply, so that the clutch tends to empty itself and to reduce the torque transmitted, simultaneously allowing the slip to increase until the torque diminishes when the original conditions are gradually restored.

In addition to the outlet valves B^4 one or more declutching valves b^3 may be provided in the rotary casing at or near the periphery thereof. This valve b^3 is preferably a spring loaded ball valve which when the clutch is rotating is forced outwards by centrifugal force against the action of a spring b^4 to close the orifice b^5 in the casing thereby preventing the escape of liquid. When the clutch is at rest the valves b^3 are opened by the springs b^4 allowing the liquid to escape from the chamber in the cover plate B^3 to the stationary casing B^5 .

In a modification a balanced pressure pis-

ton valve may be employed in place of the ball valve b^3 . The valve b^{10} shown in Fig. 6 will close under centrifugal force but is unaffected by the pressure exerted upon it by the pressure of the liquid and will open even though the pressure of liquid within the clutch is relatively high.

The cover or casing B^3 surrounding the element B^2 is bolted to the element B^1 , hydraulic thrust washers b^6 being provided on the shaft C to form a bearing surface between the element B^2 and the casing B^3 . Passages b^7 are provided between the cups in the element B^2 and the faces of the thrust washers b^6 to lubricate these faces. The passages are preferably formed in a direction substantially tangential to the periphery of the cup, so that the velocity head of the liquid coursing round the periphery of the cup is utilized to generate pressure in the annular space b^8 somewhat in excess of that which exists inside the revolving casing. The liquid therefore tends to flow radially outwards between the thrust faces which are thereby lubricated.

In the form of the invention shown in Fig. 2 provision is made for counteracting the tendency of one of the shafts to fluctuate in speed.

A centrifugal pump D mounted on the shaft C is provided to supply water to the inlet passages b^1 in the vanes through passages b^3 . The pump D receives liquid from a chamber d supplied through a pipe d^1 . The quantity of liquid discharged by the pump is controlled by a valve d^2 regulating the area of ports formed in the body of the valve and therefore restricting to a greater or less degree the discharge of liquid into the inlet passages b^8 and b^1 of the clutch. Any convenient form of valve d^2 may be utilized but the one shown is provided with a piston d^3 capable of sliding in an axial direction so as to uncover more or less the valve ports. The piston d^3 is pressed on to its seat by a spring d^4 the compression of which can be regulated by a handwheel and screwed spindle d^6 .

Assuming that the shaft C is revolving at a given speed, receiving power through the clutch and that due to a change in load to which the shaft C is subjected, the speed of the shaft C tends to rise. The pump D will automatically run faster developing greater pressure and therefore supplying liquid more rapidly to the clutch than formerly, even though the ports in the main control valve remain unaltered in area. This action will result in the clutch receiving a greater supply of liquid and consequently transmitting more power but the effect of the spring loaded piston d^3 exaggerates this result because the piston, being subjected to the greater pressure of liquid, compresses the spring d^4 increasing the area for the flow of liquid

through the valve ports and the liquid flows into the clutch at a still greater rate. The tendency for the speed of the shaft C to increase is thereby checked rapidly.

- 5 Similarly, if the speed of the primary shaft tends to fall, the liquid pressure at the pump discharge nozzle falls, the area of the valve ports is also reduced and the flow of liquid into the clutch is quickly reduced, thereby 10 diminishing the power supplied through the clutch to the shaft C. This again tends to stabilize the speed of the shaft C.

Details of three forms of discharge valve B⁴ in the casing B⁵ are shown in Figs. 3 to 6.

- 15 In Fig. 3 a ball valve f is held on its seat by a spring f¹ the pressure exerted by the spring on the ball being varied by a screw f² held in the desired position by a spring strip f³. In order to prevent the liquid discharged 20 from the valve from being thrown against the periphery of the stationary casing B⁵ a curved guide plate f⁴ is provided surrounding the valve to direct the liquid inside a catch plate f⁵ mounted on the casing B⁵.

- 25 In Fig. 4 a spring loaded mushroom valve f⁶ is shown operated through a sliding sleeve on the shaft C by a forked lever f⁷ pivoted on the casing B⁵ this lever f⁸ being either manually controlled or by a governor (not shown). In the arrangement shown in Fig. 30 5 the liquid is discharged from the clutch through passageways g communicating with a passageway g¹ in the centre of the shaft C in communication with a radial passageway g² and opening into an annular groove g³ in a lantern ring g⁴ surrounding the shaft C¹. From the lantern ring the liquid passes up the passageway g⁵ to a spring loaded ball valve g⁶ arranged to open at a predetermined 40 pressure. After passing through the valve the liquid escapes into the interior of the casing B⁵.

- What I claim as my invention and desire to protect by Letters Patent is:—
- 45 1. A hydraulic clutch of the type referred to for transmitting power comprising the combination with the driving shaft and the driven shaft of a rotor mounted on the driving shaft, a rotor mounted on the driven shaft, cups in the first rotor and coacting 50 cups in the second rotor, vanes separating adjacent cups in the first rotor, vanes separating adjacent cups in the second rotor, passages formed in the vanes for the admission 55 of cooled liquid, passages formed in the vanes for placing the centres of the vortices in communication with the atmosphere, a cover plate surrounding one rotor and bolted to the other rotor, a release valve adjacent to the axis of rotation and means to supply liquid to the cups.

- 60 2. A hydraulic clutch of the type referred to for transmitting power comprising the combination with the driving shaft and the driven shaft of a rotor mounted on the driv-

ing shaft, a rotor mounted on the driven shaft, cups in the first rotor and coacting cups in the second rotor, vanes separating the adjacent cups in the first rotor, vanes separating the adjacent cups in the second rotor, 70 passages formed in the vanes for the admission of cooled liquid, passages formed in the vanes for placing the centres of the vortices in communication with the atmosphere, a cover plate surrounding one rotor and bolted to the other rotor, a release valve adjacent to the axis of rotation and a pump to supply the liquid to the cups to counteract fluctuations in speed in one of the shafts.

3. A hydraulic clutch of the type referred to for transmitting power comprising the combination with the driving shaft and the driven shaft of a rotor mounted on the driving shaft, a rotor connected to the second shaft, cups in the first rotor and coacting cups in the second rotor, vanes separating the adjacent cups in the first rotor, vanes separating the adjacent cups in the second rotor, 75 passages formed in the vanes for the admission of cooled liquid, passages formed in the vanes for placing the centres of the vortices in communication with the atmosphere, a cover plate surrounding one rotor and bolted to the other rotor, a release valve adjacent to the axis of rotation and a pump to supply the liquid to the cups to counteract fluctuations in speed in one of the shafts.

80 4. A hydraulic clutch of the type referred to for transmitting power comprising the combination with the driving shaft and the driven shaft of a rotor mounted on the driving shaft, a rotor connected to the second

85 shaft, cups in the first rotor and coacting cups in the second rotor, vanes separating the adjacent cups in the first rotor, vanes separating the adjacent cups in the second rotor, 90 passages formed in the vanes for the admission of cooled liquid, passages formed in the vanes for placing the centres of the vortices in communication with the atmosphere, a cover plate surrounding one rotor and bolted to the other rotor, a release valve adjacent to the axis of rotation and a pump to supply the liquid to the cups to counteract fluctuations in speed in one of the shafts.

95 5. A hydraulic clutch of the type referred to for transmitting power comprising the combination with the driving shaft and the driven shaft of a rotor mounted on the driving shaft, a rotor connected to the second

100 shaft, cups in the first rotor and coacting cups in the second rotor, vanes separating the adjacent cups in the first rotor, vanes separating the adjacent cups in the second rotor, 105 passages formed in the vanes for the admission of cooled liquid, passages formed in the vanes for placing the centres of the vortices in communication with the atmosphere, a cover plate surrounding one rotor and bolted to the other rotor, a release valve adjacent to the axis of rotation and a pump to supply the liquid to the cups to counteract fluctuations in speed in one of the shafts.

110 6. A hydraulic clutch of the type referred to for transmitting power comprising the combination with the driving shaft and the driven shaft of a rotor mounted on the driving shaft, a rotor connected to the second

115 shaft, cups in the first rotor and coacting cups in the second rotor, vanes separating the adjacent cups in the first rotor, vanes separating the adjacent cups in the second rotor, 120 passages formed in the vanes for the admission of cooled liquid, passages formed in the vanes for placing the centres of the vortices in communication with the atmosphere, a cover plate surrounding one rotor and bolted to the other rotor, a release valve adjacent to the axis of rotation and a pump to supply the liquid to the cups to counteract fluctuations in speed in one of the shafts.

125 7. A hydraulic clutch of the type referred to for transmitting power comprising the combination with the driving shaft and the driven shaft of a rotor mounted on the driving shaft, a rotor connected to the second

130 shaft, cups in the first rotor and coacting cups in the second rotor, vanes separating the adjacent cups in the first rotor, vanes separating the adjacent cups in the second rotor, 135 passages formed in the vanes for the admission of cooled liquid, passages formed in the vanes for placing the centres of the vortices in communication with the atmosphere, a cover plate surrounding one rotor and bolted to the other rotor, a release valve adjacent to the axis of rotation and a pump to supply the liquid to the cups to counteract fluctuations in speed in one of the shafts.

vanes for placing the centres of the vortices in communication with the atmosphere, a cover plate surrounding one rotor, and bolted to the other rotor, a ball release valve adjacent to the axis of rotation, a casing surrounding the rotors, a catch plate mounted on the casing to receive the liquid escaping through the release valve, a pump to supply liquid to the cups and a declutching valve in the cover plate by which the clutch is emptied.

In testimony whereof I have hereunto set my hand this 23rd day of May, 1930.

GEORGE HENRY WALKER.
